(No Model.)

W. J. PONTO.
CAR COUPLING.

No. 440,058.

Patented Nov. 4, 1890.

William J. Ponto,
By L. Deane
his Attorney.

UNITED STATES PATENT OFFICE.

WILLIAM J. PONTO, OF HILLSBOROUGH, NORTH DAKOTA.

CAR-COUPING.

SPECIFICATION forming part of Letters Patent No. 440,058, dated November 4, 1890.

Application filed September 29, 1890. Serial No. 366,476. (No model.)

To all whom it may concern:

Be it known that I, WILLIAM J. PONTO, a citizen of the United States, residing at Hillsborough, in the county of Traill and State of North Dakota, have invented certain new and useful Improvements in Car-Couplings; and I do hereby declare the following to be a full, clear, and exact description of the invention, such as will enable others skilled in the art to which it appertains to make and use the same.

Figure 1 is a side elevation showing a portion of the front of a railroad freight-car and the draw-head and present invention as applied in use. Fig. 2 is a longitudinal central section of the lower end of the rod that carries at its end the coupling-pin; Fig. 3, a detail in side elevation, showing the construction and arrangement of parts by which the coupling-pin rod may be held up when desired. Fig. 4 is a detail in section, showing how the lifting-rod is jointed to the shank at the eye that engages the upper end of the coupling-pin.

This invention is chiefly an improvement on the car-coupler shown in my patent, No. 413,549, of October 22, 1889; and the novelty consists in jointing the rod that operates the coupling-pin, whereby in the movement of the cars in coupling there may be some flexibility.

I will now proceed to describe my invention in detail, reference being had to the accompanying drawings.

In the drawings, A denotes any ordinary freight-car, and B the draw-head centrally placed below it at the end, front, or rear, and through the usual spring b, having a certain amount of movement back and forth to prevent jar or breaking in coupling.

C is the bolt in the draw-head, to which is attached in the opening in the draw-head the supporting-plate c.

D is the coupling-pin, having on each side a fin d. The rod G, by which the coupling-pin is raised, is connected with the pin by an eye g and passes through the ends of projections a, attached to the car. Excepting the spring b all the above is as in my said pat-

ent. Now, in order to allow a certain degree of flexibility at the lower end of the pin-operating rod G the shank h of the eye H is jointed to the lower end of this rod at G'. This joint is made by socketing the shank at h' and inserting the lower end g of the rod G into it, as shown in Fig. 2, and then passing the pin or bolt I through the sides of the socket and end g. This bolt is at one side of the center, preferably, so as to give a better motion.

To aid in the operation of the joint, there is provided the bolt K, which fits into the central slot g' in the lower end of the rod G. By means of the spring L about this bolt its pointed lower end k is forced down into the shallow seat h² in the socket h'. By this means any trouble that could happen from a rigid connection between the coupling-pin and its lifting-rod is obviated.

To enable the lifting-rod to be held up when it is desired to have the coupling-pin up out of the draw-head, there is provided on the top of the car the spring-actuated bolt M, which is adapted to fit into the notch g² in the rod. Thus this rod may easily be held up, or by withdrawing the bolt from the notch will be allowed to drop down.

It will be obvious that by means of the joint G' and the structure above explained practically all the advantage of a single rod is obtained, because under all ordinary conditions of use this bar as a bar holds the pin vertical. It is only under the condition of coupling the car that the spring comes into use. Hence it is far preferable to a chain or other flexible connection of the lifting-rod with the coupling-pin on the shank of the eyebolt.

Having now described my invention, I claim—

1. In a car-coupler, the combination of the lifting-rod G and the eye H, joined to it at G' in the manner described, and having within the joint the spring-actuated bolt with the coupling-pin D, in the manner and for the purposes set forth.

2. The combination of the rod G, having a slot in its lower end, the bolt K, and spring

L therein with the eye H, having a socket h' in its upper end and a seat h², and the pin I, substantially as and for the purposes set forth.

5 3. The combination of the rod G, notched at g², with the spring-actuated bolt M on the top of the car, substantially as and for the purposes set forth.

In testimony whereof I affix my signature in presence of two witnesses.

WILLIAM J. PONTO.

Witnesses:

JOHN E. PAULSON,
P. S. PETERSON.
